ALLEN CURTIS, OF GLENS FALLS, NEW YORK, ASSIGNOR TO INTERNATIONAL PAPER COMPANY, OF NEW YORK, N. Y., A CORPORATION OF NEW YORK.

SHARPENING ATTACHMENT FOR WOOD-PULP GRINDERS.

1,070,328.

Specification of Letters Patent. Patented Aug. 12, 1913.

Application filed August 31, 1908, Serial No. 451,068. Renewed July 3, 1913. Serial No. 777,338.

To all whom it may concern:

Be it known that I, ALLEN CURTIS, a citizen of the United States, residing at and whose post-office address is Glens Falls, 5 Warren county, New York, have invented certain new and useful Improvements in Sharpening Attachments for Wood-Pulp Grinders; and I do hereby declare the following to be a full, clear, and exact description of the invention, such as will enable others skilled in the art to which it appertains to make and use the same.

My invention relates to certain new and useful improvements in sharpening attachments for wood pulp grinders, and is 10 designed to put at the disposition of the operator means for sharpening the grind-stone more expeditiously and with greater uniformity and certainty than has heretofore been customary in the art.

In the accompanying drawing, Figure 1 represents an end view of the main portions of a wood pulp grinder and shows the relation of the attachment for sharpening the 15 grind-stone in accordance with my invention; Fig. 2 represents, on a larger scale, a front elevation of the attachment, partly in section; Fig. 3 represents a top plan view of the attachment and shows the relation 20 of the burring or sharpening wheel to the grind-stone; Fig. 4 represents a sectional view taken on a plane indicated by the line 4, 4 of Fig. 2.

Similar letters of reference indicate similar parts throughout the several views.

Referring to the drawing, A indicates the main casing of a wood pulp grinder, provided with the usual pockets and hydraulic cylinders for presenting the wood 25 to the grind-stone, as is well understood by those skilled in the art. The attachment, constituting my invention, is secured in any suitable manner to the bed-plate or standards of the grinder, as, for instance, by 30 means of angle irons *a* bolted to the uprights *b*, which angle irons support the head portions *c* of the hydraulic cylinder *d* and the guide-way *e* of the sliding tool head *f* which is mounted upon a rod *g* attached by 35 a cross head *h* to the piston rod *i* of the hydraulic cylinder. The hydraulic cylinder, as is usual, is provided with the customary ports at its opposite ends, for the inlet and exit of the actuating fluid; whereby, through 40 the intermediacy of suitable cocks or valves

(not shown), the piston *n* of the hydraulic cylinder *d* may be carried either to the right or to the left, at the will of the operator. In so doing, the piston rod *i*, the cross rod *h* and the tool holder rod *g* partake of the motion of the piston, and therefore carry the burring or sharpening wheel *k* across the face or periphery of the rotating grind-stone B.

The burring or sharpening wheel *k*, 65 mounted in a suitable yoke, as *l*, so as to revolve freely, is adapted to be moved toward or from the grind-stone B, by means of a crank handle *m*, as is usual in devices 70 of this general character.

The operation of the invention will be apparent: The attachment, secured in place as shown and described, is normally at such adjustment that the burring wheel *k* is out of the path of movement of the revolving 75 grind-stone B and the piston *n* is at the innermost limit of its movement, in which position it is maintained, thereby withdrawing the rods *i* and *g* from projecting materially beyond the bed-plate of the machine. 80 In this adjustment, therefore, the attachment takes up but little room and its main parts are correspondingly protected against accidental breakage. When it is desired to sharpen the grind-stone, the burring or 85 sharpening wheel *k* is advanced toward the stone by means of the crank handle *m* mounted upon the usual feed screw engaging a screw-threaded nut or the like on the cross-slide to which the yoke *l* in which the burring wheel *k* is mounted, is attached. By 90 an appropriate manipulation of the hydraulic cock or cocks governing the admission and exit of the actuating fluid with respect to the hydraulic cylinder and its piston, the longitudinal slide *f* carries the burring wheel progressively across the face of the revolving grind-stone, and with a regularity and speed commensurate with the action of the hydraulic fluid upon the piston. 95 In practice, it is found feasible to carry the burring wheel across the face of the grind-stone within a very few seconds, the attention of but a single operator being required to insure its uniform and efficient action.

By reversing the position of the cock or cocks, either manually or automatically, the burring wheel, after moving entirely across the face of the grind-stone, is carried back in the opposite direction, and these reciproca- 100 105 110

tions are repeated until the grind-stone is sharpened to the desired degree. I find, in practice, that the action of the burring wheel upon the grind-stone, under the uniform 5 pull and push of the rod *g* connected to the quickly moving hydraulic piston rod *i*, is of such a character that in spite of the fact that the usual grind-stone for wood pulp grinders has softer and harder places in its periphery, there is practically no tendency for 10 the burring wheel to abrade the softer spots to a greater depth than the harder spots. This is of great importance from a practical 15 standpoint, inasmuch as the slow moving burring wheel in the machines heretofore employed have always required two men to operate them and have had a more or less unequal abrading action upon the grind-stone periphery, to such an extent that in 20 most cases it has been practically indispensable to employ after the action of the burring wheel, a supplemental hand operated jiggling mechanism, in order to remove the 25 irregularities referred to. Nothing of this kind is required or is desirable for grindstones which have been sharpened by the employment of the apparatus herein described.

Having thus described my invention, what I claim is:—

1. A wood pulp grinder provided with a 30 grind-stone-sharpener consisting of a burring or sharpening wheel, having means for moving it into contact with the grind-stone surface, a reciprocating slide for said wheel, a hydraulic piston and cylinder, and connections between the tool slide and the piston for reciprocating the burring wheel back and forth across the face of the grind-stone; substantially as described.

2. A wood pulp grinder provided with a 40 grind-stone-sharpener consisting of a burring or sharpening wheel, having means for moving it into contact with the grind-stone surface, a reciprocating slide for said wheel, a hydraulic cylinder located immediately below the slide and having a guide-way upon which the slide travels, a piston and piston-rod for said cylinder, an actuating rod for the slide, and a cross-head for connecting the piston rod and slide rod; substantially as de- 45 scribed.

In testimony whereof I affix my signature in presence of two witnesses.

ALLEN CURTIS.
